Robert G. Pearson
ATTORNEY.

UNITED STATES PATENT OFFICE.

VICTOR F. FERRON, OF LOS ANGELES, CALIFORNIA.

ABDOMINAL TRUSS.

Application filed January 26, 1926. Serial No. 83,877.

This invention is an abdominal supporter, particularly useful for supporting a hernia or the like.

The general object of the invention is to provide a simple and inexpensive abdominal supporter, or truss, which will not slip off the hernia or other injury, but will effectively maintain itself in position at all times and under all conditions of usage.

10 Other objects and advantages will appear hereinafter.

The invention is illustrated in the annexed drawing which forms a part of this specification and in which:

15 Fig. 1 is a perspective view of my supporter, or truss, shown in position on the human body supporting a hernia.

Fig. 2 is a perspective view of the pad looking at the inside thereof.

20 Fig. 3 is a transverse vertical section of the supporter taken on line 3—3 of Fig. 1.

Corresponding reference numerals designate the same parts in all the views.

My supporter comprises a belt 1, a supporting pad 2, and a balancing pad 3, the pads 2 and 3 being secured to the inside of the front portion of the belt a short distance apart.

25 The supporting pad 2 is formed with a front wall 4, a horizontal flange 5 extending rearwardly from the upper portion of said front wall and a pair of vertical end walls 6 extending rearwardly from the ends of said front wall and at the ends of said flange, 30 said end walls extending at their upper ends to the rear edge of the flange 5 and inclining forwardly and downwardly to the front wall 4 at the lower edge of said wall. 35 A recess 7 is formed by the flanges 5 and 6 in the rear of the pad 2. The upper portion 8 of the front wall 4 extends above the flange 5.

40 The supporter is placed in position by placing the supporting pad 2 over the hernia or other injury at one side of the body, and the balancing pad 3 over the corresponding position at the other side of the body, and extending the belt 1 rearwardly and securing the same around the body by any suitable securing means (not shown).

45 The pressure of the pad 2 by the belt over the hernia 10 holds the hernia inwardly of the body and presses the flanges 5 and 6 inwardly on the body around the hernia while 50 the hernia fits in the socket 7 and is held therein by said flanges so that the pad will

not slip off the hernia in any direction. The upper portion 8 of the front wall 4 engages the body to limit the inward pressure and properly positions the flange 5 in the body 60 over the hernia. The pressure of the balancing pad 3 on the side of the body opposite the side on which the supporting pad is placed, balances and gives symmetry to the supporter on the body. The flange 5 prevents the pad from slipping up or down while the flanges 6 prevent the pad from slipping endwise off the hernia.

I claim:

1. An abdominal supporter comprising a belt adapted to be extended and secured around the human body, and a pad secured on said belt to fit over an injury of the body, said pad being formed with a front wall, a horizontal flange extending rearwardly from the front wall to press inwardly into the body over and above the injury, and a pair of vertical side flanges extending rearwardly from the front wall and downwardly from said horizontal flange to press inwardly into the body at the sides of the injury, said flanges forming a recess open at its lower side to receive the injury.

2. An abdominal supporter comprising a belt adapted to be extended and secured around the human body, and a pad secured on said belt to fit over an injury of the body, said pad being formed with a front wall, a horizontal flange extending rearwardly from the front wall to press inwardly into the body over and above the injury, and a pair of vertical side flanges extending rearwardly from the front wall and downwardly from said horizontal flange to press inwardly into the body at the sides of the injury, said flanges forming a recess open at its lower side to receive the injury, the rear edges of said side flanges inclining downwardly to said front wall.

3. An abdominal supporter comprising a belt adapted to be extended and secured around the human body, and a pad secured on said belt to fit over an injury of the body, said pad being formed with a front wall, a horizontal flange extending rearwardly from the front wall to press inwardly into the body over and above the injury, and a pair of vertical side flanges extending rearwardly from the front wall and downwardly from said horizontal flange to press inwardly into the body at the sides of the injury, said flanges forming a recess open at its lower

side to receive the injury, the upper portion of said front wall extending above said horizontal flange for engaging the body to limit the inward pressure and to properly position said flange in the body over the injury.

4. An abdominal supporter comprising a belt adapted to be extended and secured around the human body, and a pad secured on said belt to fit over an injury of the body, said pad being formed with a front wall, a horizontal flange extending rearwardly from the front wall to press inwardly into the body over and above the injury, and a pair of vertical side flanges extending rearwardly

from the front wall and downwardly from said horizontal flange to press inwardly into the body at the sides of the injury, said flanges forming a recess open at its lower side to receive the injury, the rear edges of said side flanges inclining downwardly to said front wall, the upper portion of said front wall extending above said horizontal flange for engaging the body to limit the inward pressure and to properly position said flange in the body over the injury.

In testimony whereof I hereunto affix my signature.

VICTOR F. FERRON.
